United States Patent Office

Des. 227,208

Patented June 12, 1973

227,208

CHAIR

Thomas Winrow, 530 S. Sleigh,
Naperville, Ill. 60540

Filed Apr. 22, 1971, Ser. No. 136,656

Term of patent 14 years

Int. Cl. D6—02

U.S. Cl. D6—71

The figure is a perspective view of a chair illustrating my new design.

The back of the chair is conventionally plain while the side not shown is substantially identical to the side shown.

I claim:

The ornamental design for a chair, as shown and described.
